UNITED STATES PATENT OFFICE.

CHARLES H. CULPEPPER, OF PORTSMOUTH, VIRGINIA.

DESIGN FOR A TOBACCO-PIPE BOWL.

No. 38,141.

Specification for Design.

Patented July 31, 1906.

Application filed June 27, 1906. Serial No. 323,741. Term of patent 3 $\frac{1}{2}$ years.

To all whom it may concern:

Be it known that I, CHARLES H. CULPEPPER, a citizen of the United States of America, residing at Portsmouth, in the county of Norfolk and State of Virginia, have invented a new, original, and ornamental Design for Tobacco-Pipe Bowls, of which the following is a description, reference being had to the accompanying drawings, forming part thereof.

In the drawings, Figure 1 is a perspective

view of a pipe-bowl embodying the new design. Fig. 2 is a top plan view of the same.

I claim—

The ornamental design for a tobacco-pipe bowl, as shown.

CHARLES H. CULPEPPER.
